TABLET DISPENSING MACHINE

Filed Aug. 13, 1936

Inventor:

Lawrence E. Dickson,
By Dyerforth, Lee, Britton & Miles,
Atty.

UNITED STATES PATENT OFFICE

104,134

DESIGN FOR A TABLET DISPENSING MACHINE

Lawrence E. Dickson, Glencoe, Ill.

Application August 13, 1936, Serial No. 64,399

Term of patent 14 years

To all whom it may concern:

Be it known that I, Lawrence E. Dickson, a citizen of the United States, residing at Glencoe, county of Cook, and State of Illinois, have invented a new original, and ornamental Design for a Tablet Dispensing Machine, of which the following is a specification, reference being had to the accompanying drawing forming a part thereof, in which:

The figure is a perspective view of a tablet dispensing machine showing my new design.

I claim:

The ornamental design for a tablet dispensing machine, as shown.

LAWRENCE E. DICKSON.
